(57) **CLAIM**

The ornamental design for a safety clip for hypodermic needles, as shown and described.

DESCRIPTION

FIG. 1 is a top view of a safety clip for hypodermic needles showing my new design.

FIG. 2 is a bottom view thereof;

FIG. 3 is a front view thereof, a rear view being a mirror image thereof;

FIG. 4 is a left side view thereof; a right side view being identical; and,

FIG. 5 is a perspective view thereof.

1 Claim, 5 Drawing Sheets
